UNITED STATES PATENT OFFICE.

JOHN B. SUTHERLAND, OF SYRACUSE, NEW YORK, ASSIGNOR OF ONE-HALF
TO GEORGE A. PORTER, OF SAME PLACE.

VALVE-GEAR.

SPECIFICATION forming part of Letters Patent No. 317,475, dated May 5, 1885.

Application filed December 27, 1884. (No model.)

To all whom it may concern:

Be it known that I, JOHN B. SUTHERLAND, of Syracuse, in the county of Onondaga, in the State of New York, have invented new and useful Improvements in Valve-Gear, of which the following, taken in connection with the accompanying drawings, is a full, clear, and exact description.

In said drawings, Figures I and II are respectively front and side elevations of my invention; Fig. III, a top view of the bracket or pedestal which supports the moving parts of my invention. Fig. IV is a transverse section on line X X, Fig. I; and Fig. V is a vertical section of the slide which moves in a guide-groove in the stationary standard and supports the rock-arm.

Similar letters of reference indicate corresponding parts.

This invention relates to the class of steam cut-offs in which motion is transmitted from the eccentric-rod to the valve by means of a rock-arm whose fulcrum is movable longitudinally thereon and regulated in its position by the governor-spindle connected directly with said fulcrum.

My invention consists in an improved construction and combination of parts, all as hereinafter more fully described, and specifically set forth in the claims.

C represents the valve-stem, which is connected with the valve of the engine, (not shown in the drawings), and E denotes the usual eccentric-rod which receives a reciprocating motion from an eccentric attached to the driving-shaft, and usually transmits motion to the valve-stem by the medium of a link or rock-arm, the latter being in some instances mounted movably on its fulcrum and arranged to be controlled in its position by the engineer in charge, as is the case on locomotives, where the link is carried by and between two eccentric-rods and slides on a fulcrum affixed to a rock-arm which transmits motion to the valve-stem. By raising and lowering the link on its fulcrum the engineer varies the movement of the valve-stem at will.

My invention differs from the aforesaid combination and arrangement of parts, chiefly, in that the fulcrum is moved on the rock-arm automatically by the governor-spindle, thus ren-

dering the action of the valve-stem self-regulating.

To accomplish this in a positive and reliable manner, and by simple, compact, efficient, and adjustable means, I rigidly secure to the engine-bed, or to some other firm support, a bracket or pedestal consisting of an upright plate, A, which is bolted to the support, and a plate, A', bolted at one end to the part A, and formed with an offset to bring its free end some distance from and parallel with the plate A. The two plates A and A' are each provided with a vertical slot, b, and the upper portion of the plate A has a groove, a, in the form of a segment described from the center of the slot b aforesaid. In said groove moves longitudinally a segmental slide, S, to which is connected the valve-stem C by the medium of a link or strap, C', which is pivoted at opposite ends, respectively, on the slide and on the end of the valve-stem, as shown in Fig. I of the drawing. On the pin which connects the link C' with the slide is hung, by one of its ends, a rock-arm, R, which is thus connected with both the slide and valve-stem. Said rock-arm is extended through the space between the two plates A A' of the bracket, and has connected to its opposite end the eccentric-rod E. That portion of the rock-arm which lies between the plates A A' is provided with a longitudinal slot, t, and in the two slots b b of the bracket and slot t of the rock-arm slide boxes r r, through which is extended a bolt, e, constituting the fulcrum on which the rock-arm turns. To the extremities of the bolt e are attached two vertical rods, c c, which are guided and sustained in a vertical position by one of said rods sliding in a groove, f, in the back of the upper portion of the plate A. The upper ends of the rods c c are screw-threaded and indirectly connected with each other by a cross-bar, g, which is provided in its two ends with eyes, by which it is slipped onto the ends of the rods. By means of nuts n n on the rods above and below the cross-bar the latter is sustained adjustably in its position and adapted to be raised or lowered as may be necessary to obtain the desired effect from the governor, presently explained.

G denotes a common steam-engine governor, which, owing to the want of room, is shown

on a reduced scale. It comprises vertically vibratory gravitating arms, which are made to swing about a vertical spindle by rotary motion, transmitted to the support of said arms from a rotary shaft in the usual and well-known manner, said governor-arms being connected with the vertical governor-spindle C by links m m in such a manner as to cause said spindle to be moved vertically by the vertical vibration of the governor-arms, incident to the centrifugal force produced by their swinging movement about the governor-spindle. The governor being secured to a firm support above the cross-bar g, hereinbefore described, the lower end of the spindle l passes through a hole in the said cross-bar g, and is screw-threaded for the reception of nuts n' n' above and below said cross-bar.

The operation of my invention is as follows:

- 20 When the engine is at rest and the governor-arms in their normal position, the governor-spindle l is depressed, and by the medium of the cross-bar g and rods c c, pushes down the fulcrum e to the lower ends of the slots b b and t, respectively, of the bracket A A' and rock-arm R, the valve-stem thus being allowed its maximum stroke to freely admit steam to the cylinder when starting the engine. As the engine gains in velocity, the governor-arms are thrown outward by the increased centrifugal force exerted on said arms, thereby causing the governor-spindle l to draw up the fulcrum e by means of the rods c c and cross-bar g. The aforesaid movement of said fulcrum carries it toward that end of the rock-arm which is connected with the valve-stem, and correspondingly increases the distance from the fulcrum to the end of the rock-arm to which the eccentric is connected,
- 30 and therefore diminishes the stroke of the valve-stem. The resultant check of the flow of steam to the cylinder reduces the speed of the engine, and causes the governor-arms to gradually descend until they have pushed the governor-spindle down sufficiently to bring the fulcrum e in such relative position on the rock-arm as to again afford to the valve-stem a stroke which prevents further reduction of the speed of the engine.
- 40 The described action of the governor-spindle on the fulcrum e can be properly adjusted by shortening or lengthening the connection of said parts, which is effected by means of the nuts n n and n' n', hereinbefore described.
- 45 Having described my invention, what I claim as new, and desire to secure by Letters Patent, is—

1. In combination with the governor, valve-

stem, and eccentric-rod, the bracket A A', secured stationary in its position and provided with the guide-groove a and slots b b, the slide S, moving in the groove a and having connected with it the valve-stem, the rock-arm R, connected at one end with the valve-stem, and at the opposite end with the eccentric-rod 65 and provided with the slot t, the fulcrum e, sliding in the slots t and b b, and the governor-spindle connected with said fulcrum, substantially as set forth and shown.

2. In combination with the governor, valve-stem, and eccentric-rod, the bracket A A', secured stationary in its position and provided with the segmental guide-groove a and vertical slots b b, the segmental slide S, moving in the groove a, the link C', connecting the valve-stem with said slide, the rock-arm R, connected at one end with the slide at the attachment of the link and having connected to its opposite end the eccentric-rod and provided with the slot t, the fulcrum e, sliding in the 80 slots t b b, and the governor-spindle connected with said fulcrum, substantially as described and shown.

3. In combination with the governor, valve-stem, and eccentric rod, the bracket A A', secured stationary in its position and provided with the segmental groove a and vertical slots b b and f, the segmental slide S, moving in groove a, the link C', connecting the valve-stem with the slide, the rock-arm R, connected 90 at one end with the slide at the attachment of the link and having connected to its opposite end the eccentric-rod and provided with the slot t, the fulcrum e, sliding in the slots t b b, the rods c c, connected at one end with the 95 fulcrum e and guided in the groove f and screw-threaded at the opposite end, the cross-bar g, connecting the rods c c, nuts n n, for adjustably sustaining the cross-bar on said rods, the governor-spindle having its end 100 screw-threaded and passing through the cross-bar g, and nuts n' n' for adjustably connecting the governor-spindle with the said cross-bar, all constructed and combined to operate substantially in the manner specified and shown. 105

In testimony whereof I have hereunto signed my name and affixed my seal, in the presence of two attesting witnesses, at Syracuse, in the county of Onondaga, in the State of New York, this 11th day of December, 1884.

JOHN B. SUTHERLAND. [L. S.]
